UNITED STATES PATENT OFFICE.

JAMES POWERS, OF LOS ANGELES, CALIFORNIA.

TOOTHPICK CUTTER AND DISPENSER.

Application filed February 4, 1919. Serial No. 274,939.

To all whom it may concern:

Be it known that I, JAMES POWERS, a citizen of the United States, residing at Los Angeles, in the county of Los Angeles and State of California, have invented a new and useful Toothpick Cutter and Dispenser, of which the following is a specification.

This invention has reference to toothpick cutters and dispensers, and its object is to provide a sanitary dispensing apparatus for toothpicks whereby the toothpicks are individually cut and delivered, as needed, by a customer desiring toothpicks, and are at all times protected from indiscriminate handling, while unnecessary waste of toothpicks is avoided.

The invention is intended particularly for use by the public where the article delivered is to be placed in the mouth. Ordinarily, toothpicks are offered to the public in restaurants, lunch rooms and other public eating places, in large or small receptacles, so that a customer in selecting a toothpick out of such receptacles cannot avoid touching, with the fingers, numerous toothpicks before one can be extracted for use. It is practically unavoidable that after a meal the fingers of the individual are not absolutely clean and there is no assurance that some, at least, of the individuals have not some disease which may be communicated by the toothpicks unintentionally handled. Furthermore, it is a very common custom in public places for individuals to indulge in extra helpings of toothpicks so that the supply of toothpicks represents a considerable expense to the management of eating places. Again, the handling of the toothpicks and placing them in the containers presents another element of uncleanliness to be done away with.

All these objectionable features are avoided by the invention, which provides toothpick stock in the shape of relatively long strips which, in cross section, correspond to the shape of a toothpick and which strips may be made of veneer and may be furnished in rolls or coils wrapped to avoid contact in handling the toothpick stock, whereby the chance of contamination in transit and when placing the stock in position for cutting and dispensing, is eliminated.

The invention contemplates the use of mechanism by which the toothpick stock in

the shape of a long band of veneer is fed to a cutter which may be of the reciprocatory type and which, at each stroke, will sever a single toothpick from the strip and deliver it into position to be reached by a customer without being handled by any other person. Moreover, the invention provides for the customer to be the operator of the mechanism which delivers a single toothpick and individualizes it to the customer. In this way chance of contamination is avoided and as the customer can get but one toothpick at a time the liability of waste by extra helpings, as where toothpicks are freely available, is done away with, without, however, preventing the customer from obtaining more than one toothpick if he so desires.

The invention further contemplates the use of a transparent guard plate covering the cutter whatever its position and absolutely preventing the customer or any other person from handling the toothpick stock or the cutter. Thus all danger of injury to the fingers is eliminated and no danger of communicating disease by contamination of the knife can arise. While the end of the veneer band always projects from the main body of the dispenser, no fingers can reach to it because of the guard.

The invention will be best understood from a consideration of the following detailed description taken in connection with the accompanying drawings forming part of this specification, with the understanding, however, that the invention is not confined to any strict conformity with the showing of the drawings, but may be changed and modified so long as such changes and modifications mark no material departure from the salient features of the invention as expressed in the appended claims.

In the drawings:—

Figure 1 is a front elevation of the machine of the invention.

Figure 2 is a front to rear section of the structure shown in Figure 1, with some parts nearer than the line of section shown in elevation.

Figure 3 is a section on the line 3—3 of Figure 2.

Figure 4 is a side elevation of the machine shown in Figure 1, with the manipulating arm in cross section and some parts omitted.

Figure 5 is a perspective view of a small portion of the veneer strip from which the toothpicks are made.

Referring to the drawings, there is shown

5 a casing 1 composed of a bottom plate or casting 2 with upstanding blocks 3 on opposite sides, and an upstanding front casting 4 fastened by screws 5 to the blocks 3 and provided at the top with an outstanding flange 4^a. The opposite sides of the casing are shown in the form of sheets 6, 7 respectively, preferably of metal, each sheet from about mid-height to the top having an overhang portion 8 somewhat wider than the flange 4^a 10 and at the outer edge having an inturned flange 9, whereby to secure a glass pane 10 displaying certain portions of the interior mechanism of the casing located on the outer face of the front casting 4. The back and 15 top of the casing may comprise a single sheet 11 of metal having a hinge connection 12 at the lower rear end with the bottom 2, and at the upper portion bent toward the front of the machine. The sheet 11 is again bent, as 20 shown at 13, to form the top of the casing and engage over the flange 4^a where a lock, indicated at 13^a may be provided. In this manner authorized access to the interior of the machine may be conveniently had at any 25 time by turning the back and top portion of the machine on the hinge 12. The glass pane 10 is spaced forwardly from the front board or partition 4 forming a chamber or compartment 10^a with a passageway 14 at 30 the lower end to constitute a discharge opening. Underlying the compartment 10^a is a tray or trough 15 which may be conveniently made of sheet metal appropriately bent into shape, and continued to the bottom of the 35 machine in front of the casting 4 to constitute a finish, the sheet metal being held in place by screws 16 or the like.

Extending through the front casting 4 behind the glass pane 10 and at an appropriate distance above the discharge opening 10^a is a slot 17 which may taper toward the front and is a little longer than the length of a toothpick. Secured to the front 4 on the outer face thereof is a wear plate 18 which 40 may be of hardened steel and has a slot or passage 19 in front and forming a continuation of the slot 17. In front of the wear plate 18 is a shear blade 20 capable of vertical movement across the slot 19; the bottom edge of the latter constitutes a fixed shear blade. The blade 20 is held to the plate 18 by screws 21 extending through slots 22 in the blade 20 so that the blade may have a limited up and down movement 45 guided by the screws 21. The lower end of the blade 20 has a beveled cutting edge 23 so as to produce a shear cut across the slot 19. Attached to the wear plate 18, near the upper end of chamber 10^a, is a lever 24, the 50 means of attachment being a pivot screw 25

extending through one end of the lever. The other end of the lever projects through an elongated vertical slot 26 in the side plate 7, and exterior to the casing this lever is formed into a manipulating handle 27.

About midway of the length and width of the blade 20 there is attached thereto, by means of a screw 28, a link 29 also attached by a screw 30 to the lever 24 about midway of its length. A spring 31 secured at one end to a fixed part of the structure, say, the screw 25, engages the under edge of the lever 24 and so normally holds the lever and the blade 20 in the elevated position. Formed through the front board or partition 4 and 70 wear plate 18 is a curved slot 32 with the curvature described about the axis of movement of the lever 24. Extending through the slot 32 is a pin 33 entering the casing back of the front or partition 4, the pin 33 80 participating in movements of the lever 24 about its pivot screw 25.

Fast to the rear face of the front board or partition 4 are brackets 34 constituting journal bearings for a rock shaft 35, which shaft 90 carries roughened or milled feed wheels or rollers 36 spaced apart an appropriate distance on the shaft 35. At one end the shaft 35 has fast thereto a ratchet wheel 37 and mounted at one end on the shaft 35 to turn 95 loosely thereon is an arm 38 carrying a pawl 39 engaging the teeth of the ratchet wheel 37. The arm 38 is an upstanding arm and has an elongated bearing face 40 at its upper end in position to be engaged by the pin 33. 100 A spring 41 fastened at one end to the front or partition 4 and at the other end to the arm 38 has a constant tendency to urge the arm 38 toward the front board or partition 4. Below the face 40 the arm 38 has a cut-away or bevel portion 42, the face 40 being of less length than the travel of the pin 33 105 lengthwise of the arm. The bevel 42 is so proportioned that when the pin 33 reaches it the spring 41 will move the arm 38 toward 110 the front or partition, thus carrying the pawl 39 idly over one tooth of the ratchet 37. This occurs during the downward or cutting stroke of the blade 20. When the handle 27 is released and the blade 20 is 115 raised by the spring 31 the pin 33 engages the bevel 42 and thereby forces the arm 38 away from the partition 4, thus turning the ratchet 37 a distance of one tooth.

Below the slot 17 and in or approximately 120 in the plane of the shaft 35 is another shaft 43 carrying plain or smooth supporting rollers 44. The shaft 43 is journaled at the ends in rock arms 45 fast on a shaft or arbor 46 carried by brackets 47 fast on the partition 4. The shaft 46 is surrounded by 125 springs 48, each at one end 49 engaging a respective arm 45 and at the other end 50 engaging against the inner face of the partition 4. The tendency of the springs 48 is 130

to move the rollers 44 towards the rollers 36.

There is also provided a strip 51 of wood veneer from which the toothpicks are to be made. The edge portions 52 of the strip 51 are beveled so that in cross section the strip 51 corresponds to the shape of a double-pointed toothpick of familiar form. It will be understood, however, that other shapes may be used. The strip 51 passes between the rollers 36 and 44 and is gripped thereby. The rollers 36, each time the arm 38 is forced against the action of the spring 41 by the rising movement of the pin 33, feed the strip 51 a distance corresponding to the width of a toothpick, the strip being thereby fed beyond the slot 19 in the wear plate 18 a like distance. When the handle 27 is manipulated by a customer to lower the blade 20 a toothpick is severed from the strip 51 and falls through the discharge opening 14 into the trough 15 within easy reach of the customer. On releasing the handle 27 the parts are returned to their first position by the spring 31 and the strip 51 is fed beyond the outer face of the wear plate 18 a distance sufficient to provide for the cutting off of another toothpick from the strip 51.

To economize space the strip 51 is rolled up into a coil, as shown in Figure 2, in which form the strip 51, constituting toothpick stock, may be furnished wrapped to avoid contamination in handling. A curved guard plate 53 is carried by the blocks 3 to prevent interference of the strip with parts in front of it.

It will be seen that the structure shown and described provides for the cutting and dispensing of toothpicks, one at a time and individualized to the customer, by mechanism manipulated by a customer desiring a toothpick. But one toothpick is formed at a time and one toothpick is usually all a customer desires. If more than one toothpick is wanted then it is necessary to manipulate the machine as many times as there are toothpicks desired. There is no handling of the toothpicks except those delivered directly to the customer and the toothpick stock is thoroughly protected from handling by the customers or others. The glass pane 10 forms a guard for the cutter, preventing accidental injury to the fingers, preventing handling of the knife, keeping the fingers away from the end of the toothpick stock, providing a chute down which the cut toothpicks may fall, and permitting each customer to see with his own eyes that he is obtaining a toothpick made for and by himself alone. The structure is therefore of particularly sanitary character, and, furthermore, there is no incentive for a customer to take many toothpicks at a time simply because they are accessible. The invention therefore contributes toward economy as well as sanitation for, although toothpicks

are very cheap, the amount of wastage due to customers taking many toothpicks, will in large establishments, represent a material amount of money in the course of a year.

What is claimed is:

1. A device of the character described comprising bottom and front members fastened together, sides fast to the bottom and front members and having forwardly projecting overhang parts, the front member having a transverse slot therethrough between the overhang parts of the sides and also having a forwardly projecting top flange, and a rear and cover member completing the casing and closing the interior of the casing against unauthorized access, said casing having a transparent pane between the overhang members and separated from the front of the casing by the top flange of said front to form an open-bottom compartment, feeding mechanism for toothpick stock in the form of a veneer strip housed within the main body of the casing and movable through the slot in the front of the casing into the front compartment, said feeding mechanism being carried by the rear face of the front of the casing, a shear blade carried by the front face of the front of the casing within the compartment thereon and movable across the slot to shear off toothpicks from the toothpick stock, spring means for maintaining the shear blade in a normally inactive position, said blade having a range of movement above the lower open end of the compartment whereby the latter serves as a guard for said blade and for the projecting end of the tooth pick stock and a manipulating lever connected to the blade and provided with a handle extending through the side of the casing for access by the customer, said lever having means for actuating the feeding mechanism in alternation with the active movement of the blade, whereby the customer may sever a single toothpick from the toothpick stock in plain sight of for delivery directly to the customer from the bottom of the front compartment, with the return of the blade and lever to normal position causing the feed of the stock into the front compartment for a distance equal to the width of a single toothpick.

2. A device of the character described comprising bottom and front members fastened together, sides fast to the bottom and front members and having forwardly projecting overhang parts, the front member having a transverse slot therethrough between the overhang parts of the sides and also having a forwardly projecting top flange, and a rear and cover member completing the casing and closing the interior of the casing against unauthorized access, said casing having a transparent pane between the overhang members and separated

from the front of the casing by the top flange of said front to form an open bottom compartment, feeding mechanism for toothpick stock in the form of a veneer strip housed within the main body of the casing and movable through the slot in the front of the casing into the front compartment, said feeding mechanism being carried by the rear face of the front of the casing, a shear blade carried by the front face of the front of the casing within the compartment thereon and movable across the slot to shear off toothpicks from the toothpick stock, spring means for maintaining the shear blade in a normally inactive position, said blade having a range of movement above the lower open end of the compartment, whereby the latter serves as a guard for the blade and for the projecting end of the tooth pick stock and a manipulating lever connected to the blade and provided with a handle extending through the side of the casing for access by the customer, said lever having means for actuating the feeding mechanism in alternation with the active movement of the blade, whereby the customer may sever a single toothpick from the toothpick stock in plain sight for delivery directly to the customer from the bottom of the front compartment, with the return of the blade and lever to normal position causing the feed of the stock into the front compartment for a distance equal to the width of a single toothpick, said casing also being provided with a trough or hopper immediately beneath the lower end of the front compartment to receive the severed toothpick from the casing and present it in accessible position to the customer.

3. A device whereby a narrow article may be cut as occasion requires, and such articles and the operation of cutting them be supervised, comprising an enclosure adapted to receive a supply of material to be cut, a wall forming one side of said enclosure having an opening therethrough, means in the enclosure for feeding material through said opening, a knife operating across the opening on the other side of the wall, and a compartment enclosing the knife throughout its range of operation, said compartment being of such a character and extending sufficiently below the opening and having itself a discharge opening for the cut article, whereby the human hand is excluded from the compartment and from the knife, so that the cutting is done under sanitary conditions, and one wall of the compartment being transparent, whereby the operation of cutting may be observed.

4. A device whereby a narrow article may be cut as occasion requires, and such articles and the operation of cutting them be supervised, comprising an enclosure adapted to receive a supply of material to be cut, a wall forming one side of said enclosure having an opening therethrough, means in the enclosure for feeding material through said opening, a knife operating across the opening on the other side of the wall, said feeding means including rollers engaging opposite sides of the material to be cut, and pawl and ratchet means for rotating the rollers, a rock arm carrying the ratchet and provided with plane and beveled portions, a pin carried by the knife and movable therewith to engage the plane and beveled portions of the rock arm, whereby return movement of the blade following cutting of the narrow article brings about feeding of the material, and a compartment enclosing the knife throughout its range of operation, said compartment being of such a character and extending sufficiently below the opening and having itself a discharge opening for the cut article whereby the human hand is excluded from the compartment and from the knife, so that the cutting is done under sanitary conditions, and one wall of the compartment being transparent, whereby the operation of cutting may be observed.

In testimony, that I claim the foregoing as my own, I have hereto affixed my signature.

JAMES POWERS.
